UNITED STATES PATENT OFFICE

LEWIS M. HULL, OF MOUNTAIN LAKES, NEW JERSEY, ASSIGNOR TO RADIO FREQUENCY LABORATORIES, INCORPORATED, OF BOONTON, NEW JERSEY, A CORPORATION OF NEW JERSEY

AMPLIFIER CIRCUIT

Original application filed November 17, 1926, Serial No. 148,975. Patent No. 1,663,151, dated May 1, 1928.
Divided and this application filed March 18, 1928. Serial No. 261,292.

This application is a division of my co-pending application Serial No. 148,975, filed November 17, 1926.

This invention relates to an electrical amplifier circuit for use in association with a four-electrode vacuum tube of the type having an emitting cathode, an anode, and two grid electrodes. For many purposes it is desirable to operate such a vacuum tube according to a method, known in this art, which includes employing the grid G_1 , which is next the cathode, or which is the inner grid in a concentric arrangement, as the control element, and giving to the grid G_2 , which is next the anode, a positive bias.

This method of operating a four-electrode tube makes use of what may, for convenience, be termed the "emission-shield" effect of the grid G_2 . The result is an increase in the effective alternating current plate impedance of the tube, due to the fact that the effect of the plate voltage upon the total electric field attracting the space current to the plate is greatly reduced by the shielding action of the grid G_2 . Another effect is the reduction of the effective inter-electrode tube capacity between the control grid G_1 and the plate, and a consequent reduction of undesirable retroactive currents which are fed back from the output circuit to the input circuit, through these tube capacities.

This method of operating a four-electrode vacuum tube as an electrical amplifier does not, in many instances, accomplish of itself a sufficient suppression of these undesirable currents. This invention relates to means for reducing or suppressing these undesirable feed-back currents in a four-electrode vacuum tube when operated as an electrical amplifier in the manner described.

I have found that by impressing upon the grid, G_2 , a voltage having the proper amplitude and phase relation, as will be later explained, to the voltage of the control grid G_1 , I can reduce to any desired extent, or sup-

press, the undesirable feed-back currents which otherwise flow through the tube capacities.

This may be accomplished in various ways, certain typical ones of which I will now describe in connection with the accompanying drawings.

Figures 1, 2, 3, and 4 are diagrams illustrating certain specific embodiments of my invention.

Figure 1 shows a four-electrode vacuum tube having emitting-cathode F , anode P , (control) grid G_1 , a second (emission-shield) grid G_2 , and input and output circuits C_1-L_1 , and C_2-L_2 , respectively. The input and output circuits may be tuned or not as desired. They are here shown as being tuned, but in the case of a cascaded amplifier having two or more stages I may use, for example, transformer coupling between the stages, and may tune only the transformer secondaries. This is shown in Figure 4. In a cascade arrangement, direct or other coupling may equally be used. The input or output circuits may be untuned, whether the audions are cascaded or not. The "A", "B", and "C" batteries are arranged as usual. The grid, G_2 , is connected to the filament through coil L_3 , which is coupled to coil L_1 in the input circuit. The proper positive bias is imparted to the grid G_2 , by including more or less of the "B" battery in this lead, or otherwise.

In this case coil L_3 should be so wound with respect to L_1 that the compensating voltage impressed upon G_2 is opposite in phase to the voltage on the grid G_1 . The amplitude of the compensating voltage may be adjusted to give the desired suppression of the feed-back currents. This may be done by giving L_3 and L_1 the proper coupling or in other ways. Various values of the coupling coefficient between these coils are suitable; I have used a coefficient of coupling equal to .5 with satisfactory results. The

operation of my circuit is not dependent upon the use of substantially unity coupling between these coils, as is the case with certain other circuits, for example that known as the neutrodyne. In some instances I find it advantageous to employ capacity C_g connected between the grid G_2 and the plate, as in Figs. 1, 3 and 4, or between the grids G_1 and G_2 , as in Figure 2. The dotted lines showing the external capacity C_g in the several figures indicate that this capacity may be employed or omitted, as desired. When employed, the capacity of C_g may, of course, be suitably adjustable.

15 An arrangement like that shown in Fig. 1 produces other beneficial results in addition to the suppression of feed-back currents. An important advantage arises from the secondary control effect exerted by the grid G_2 , in virtue of the coupling between coils L_1 and L_3 . This control effect may be of such a nature that more constant amplification is obtained over a range of wavelengths.

20 In Figure 2 the compensating voltage is applied to the grid G_2 by means of coil L_3 coupled to coil L_2 of the output circuit. The coil L_3 should be so wound with respect to L_2 that the voltage upon G_2 is in phase with the voltage upon G_1 at resonance; that is, the 25 voltage upon G_2 is opposite in phase to the voltage upon the anode, P. The remainder of the circuit may appropriately be arranged as before.

25 In this arrangement, in addition to the suppression of feed-back currents, the secondary control effect of grid G_2 tends to increase the amplification of the vacuum tube.

30 Figure 3 shows an arrangement for applying the compensating voltage to the grid G_2 by means of coil L_3 in series with coil L_1 of the input circuit, but not necessarily coupled thereto. An isolating condenser C^1 is then employed, and the tuning condenser C_1 may be connected across both coils L_1 and L_3 as shown.

35 Figure 4 has already been referred to in describing Fig. 1. It shows one suitable method of cascading a plurality of vacuum tube amplifiers arranged according to this invention. The circuit of Figure 1 is here illustrated in cascade by way of example only. The circuits as shown in the other figures may also be cascaded.

40 The circuits herein shown are of course merely typical of the means which I have found by experiment to be appropriate for carrying out my invention, by impressing the proper compensating voltage upon the grid G_2 . Equivalent circuits for accomplishing this result, or variations of the circuits shown, fall within my invention.

I claim:

45 1. An electrical amplifier circuit comprising an electron tube device having an emitting cathode, an anode, a control grid, and

a second grid, said grids being positioned in the field between said anode and cathode; an output circuit associated with said cathode and anode; and an input circuit including inductance having one terminal connected to said control grid, an intermediate point connected to said cathode, and a second terminal connected to said second grid. 70

2. An electrical amplifier circuit comprising an electron tube device having an emitting cathode, an anode, a control grid, and a second grid, said grids being positioned in the field between said anode and cathode; an output circuit associated with said cathode and anode; and an input circuit including inductance having one terminal connected to said control grid, an intermediate point connected to said cathode and a second terminal connected to said second grid, and a tuning condenser connected across said inductance. 75 80 85

3. An electron tube device having an emitting cathode, an anode, a control grid, and a second grid, said grids being positioned in the field between said anode and cathode; an output circuit associated with said cathode and anode; and an input circuit including a coil connected between said control grid and said cathode, and a second coil connected in series therewith between said cathode and said second grid and wound substantially continuously with said first coil. 90 95

4. An electron tube device having an emitting cathode, an anode, a control grid, and a second grid; an output circuit associated with said cathode and anode; and an input circuit including a coil connected between said control grid and said cathode, and a second coil connected in series therewith between said cathode and said second grid but substantially uncoupled to said first coil. 100 105

5. An electron tube device having an emitting cathode, an anode, a control grid, and a second grid, said grids being positioned in the field between said anode and cathode; an output circuit associated with said cathode and anode; and an input circuit including a coil connected between said control grid and said cathode, and a second coil connected in series therewith between said cathode and said second grid, the winding of said coils forming a substantially continuous inductive path between said control grid and said second grid. 110 115

6. An electron tube device having an emitting cathode, an anode, a control grid, and a second grid; an output circuit associated with said cathode and anode; and an input circuit including a coil connected between said control grid and said cathode, and a second coil connected in series therewith between said cathode and said second grid, the winding of said coils forming a substantially continuous inductive path between said control grid and said second grid but said coils 120 125 130

being conductively separated from each other by an isolating condenser.

7. An electron tube device having an emitting cathode, an anode, a control grid, and a second grid, said grids being positioned in the field between said anode and cathode; an output circuit associated with said cathode and anode; and an input circuit including a coil connected between said control grid and said cathode, a second coil connected in series therewith between said cathode and said second grid and wound substantially continuously with said first coil, and a tuning condenser connected across said coils.

15 In testimony whereof, I affix my signature.
